UNITED STATES PATENT OFFICE

JAMES F. GILKERSON, OF MILWAUKEE, WISCONSIN

CUSHION SHOE

Application filed September 3, 1929. Serial No. 390,181.

The invention relates to shoes and more particularly to Goodyear welt shoes having sewed heel seats.

The general object of the invention is to provide a cushioned sole shoe of the Goodyear welt type having sewed heel seats and heels secured thereto by nails or similar fastening devices, which may be expeditiously produced without special changes in factory equipment or at a materially increased cost over that required for the manufacture of the usual Goodyear welt shoes and produce a very comfortable and long-lived shoe.

A further object of the invention is to provide a cushion member of soft rubber that is interposable between the inner and outer soles of a Goodyear welt type shoe having sewed heel seats that takes the place of the usual relatively non-yielding bottom filler at the heel seat portion of the shoe.

The invention further consists in the several features hereinafter set forth and more particularly defined by claims at the conclusion hereof.

In the drawings Fig. 1 is a bottom plan view of a shoe embodying the invention, parts of the outsole being broken away;

Fig. 2 is a detail sectional view taken on the line 2—2 of Fig. 1;

Fig. 3 is a detail sectional view taken on the line 3—3 of Fig. 1;

Fig. 4 is a detail view taken generally in section along the line 4—4 or Fig. 1;

Fig. 5 is a detail perspective view of the cushion sole embodying the invention.

As previously noted, this invention relates to Goodyear welt shoes in which the heel seat is sewed and as such the shoe includes the usual upper 7, which may have a lining 8 and counter 9 associated therewith, these parts being secured in the usual manner to the flange portion 10 of the insole 11 and to the welt 12 by the inseam stitching 13, the welt 12 extending about the entire shoe.

According to the present invention, after the inseaming operation the cushion sole 14 is secured in place. This sole 14, of soft rubber, preferably molded sponge rubber, is formed to provide a heel portion and a flexible shank and sole portion 15 and from Figs. 2 and 5

it will be noted that the heel portion includes a cushion part 16 which extends up into the space formed between the inseam ridges 17 and the bottom of the insole 11 and includes the part 18 which forms a cushion heel that projects beyond the cushion part 16 forming a flange 19 which extends over the inseam ridge 17 at the heel seat. It will also be noted from Figs. 1, 3 and 4 that the flexible shank and sole portion 15 is disposed in the space between the inseam ridges 17 and the bottom of the insole in the space usually occupied by the relatively unyielding bottom filler so that it provides not only a cushioned shank, but a cushion for the ball of the foot. It may extend over the entire sole but inasmuch as the greater pressure comes on the ball of the foot the same stops short of the toe in the present instance and this space is filled with the usual bottom filler 20. This sole 14 is placed in position after the inseaming operation and secured against the insole and the inseam by suitable cement or adhesive.

Thereafter the outsole 21 is secured to the shoe by stitching 22 extending through the welt and outsole around the entire shoe, the heel seat portion of said outsole being recessed or hollowed out, as indicated at 23 in Figs. 2 and 4, so that a substantial heel cushion of the soft rubber may be obtained and so that this cushion may project over the inseam ridge and yet not interfere with the stitching of the outsole to the welt at the heel seat.

Thereafter a heel 24 of the usual rubber or leather type is secured to the heel seat portion of the shoe by nails 25 or similar fastening means which pass through the outer sole and find anchorage therein, principally in the thicker parts of the heel seat portion of said sole. In the present instance the heel 24 is shown as a rubber heel and the nails 25 pass through the outer sole adjacent the inseam ridge.

The cushion sole 14 constructed and arranged as previously described does not alter the outer appearance of the finished shoe, but does provide an extremely comfortable and lasting cushioning construction at only a

small increase in cost over the usual unyielding Goodyear welt type shoe.

I desire it to be understood that this invention is not to be limited to any particular form or arrangement of parts except in so far as such limitations are specified in the claims.

What I claim as my invention is:

1. In a Goodyear welt shoe having a sewed heel seat, the combination with the inner sole, the welt, the inseam ridge and the outer sole, of a cushion sole interposed between the inner and outer sole comprising a soft rubber member having a cushion portion extending under the insole between the inseam ridges of the heel and shank of the shoe and secured thereto and having a heel portion extending under the inseam ridge, stitching securing the welt and outer sole directly together at the outer edge of the heel seat portion of the shoe, a heel, and fastening means for said heel attached to said outer sole.

2. In a Goodyear welt shoe having a sewed heel seat, the combination with the inner sole, the welt, the inseam ridge and the outer sole, of a soft rubber cushion sole interposed between the outer and inner soles and filling the space between the inseam ridges and secured to the inner sole, said cushion sole extending over the heel and shank portions of the shoe and having a heel portion of greater thickness than the height of the inseam ridge, the outer sole being recessed at the heel portion, stitching securing the welt and outer sole directly together at the outer edge of the heel seat portion of the shoe, a heel, and fastening means for said heel attached to said outer sole.

3. In a Goodyear welt shoe having inner and outer soles and a welt inseamed to the upper materials at the heel seat, the combination of a cushion sole of sponge rubber interposed between the inner and outer sole and having a cushion portion extending under the insole between the inseam ridges of the heel and shank of the shoe and secured thereto, the outer sole lying against said cushion sole, stitching securing the welt and outer sole directly together at the outer edges thereof and around the shoe, a heel, and fastening means for said heel attached to said outer sole.

4. In a Goodyear welt shoe having inner and outer soles and a welt inseamed to the upper materials at the heel seat, a heel construction comprising a cushion member of soft rubber interposed between the inner and outer soles at the heel seat and providing a cushion heel portion and having a flanged part extending under the inseam ridge, stitching securing the welt and outer sole directly together at the outer edge of the heel seat, a heel, and fastening means for said heel attached to said outer sole.

In testimony whereof, I affix my signature.

JAMES F. GILKERSON.
